UNITED STATES PATENT OFFICE

2,470,236

PACKAGE OPENER

Elliot Charlop, New York, N. Y.

Application September 5, 1945, Serial No. 614,555

26 Claims. (Cl. 30—2)

1

This invention relates to a package opener. It comprises means for holding a package containing cigarettes or the like and mechanism for slitting the package part way across one end and pushing out some of its contents. In a simplified form of the device the pushing means may be omitted.

Throughout the specifications, including the claims, cigarette packages will be specified, but it is to be understood that I am not limiting myself to such, where consistent with the context, as packages having other contents may be operated upon.

The package is slit partially across at one end of the cigarettes, the slit extending from the narrow side of the package without injury to the cigarettes contained therein. The flap thus produced, in one form of my device, may be left on the package to form a protection for the cigarettes. In another form of the device, additional cutting mechanism is provided to cut off the flap.

The package is advanced into a rotating cutting edge which slits the wrapper. The cutting edge is that of a circular knife and driving means are provided for the knife which provides different portions of the circumference of the knife for the slitting of successive packages to prevent excessive wear at any one portion of the cutting edge. For safety, the knife is enclosed in a casing.

Another object of the invention is the automatic gauging of the package at the sidewall adjacent the knife so that the latter will slit the wrapper or cover at the proper distance from the end of the package. This is important to prevent injury to the cigarettes as while the cigarettes are produced in accurate lengths, the wrapper may enclose them with varying amounts of looseness. In one form of my device, while the spacing of the side walls where the package is inserted may be more than the length of the package for its easy insertion into the casing, yet in the vicinity of the knife the walls are accurately gauged so that the end of the package adjacent the knife is pressed against the side wall adjacent the knife, the latter being mounted in close proximity to the latter sidewall with its axis of rotation substantially perpendicular thereto. In another form of the device, the spacing of the side walls at the knife is not depended upon, but spring means are provided so that as the package is moved past the knife for the slitting of its wrapper, the end of the package at the knife is pressed against the side wall adjacent the knife.

Other objects and advantages will become ap-

2

parent upon further study of the description and drawings in which—

Fig. 1 is an isometric view of the package opener.

Fig. 2 is an isometric diagram of the knife and package shown by themselves to illustrate the slitting action of the knife.

Fig. 3 is an isometric diagram of the package by itself shown slit, and with an arrow indicating the action of the pusher in pushing out a few cigarettes.

Fig. 4 is an elevation of the knife and overrunning clutch shown by themselves.

Fig. 5 is an elevation looking into the back of the machine, that is along the line 5—5 on Fig. 6, the stay under the knife being omitted for clarity.

Fig. 6 is section, to a smaller scale than Fig. 5, looking along the line 6—6 of Fig. 5.

Fig. 7 is a partial elevation to a smaller scale showing a modified form of the device, in which a leaf spring is provided for forcing one end of the package against the sidewall adjacent the knife.

Fig. 8 is substantially an isometric view of the portion of the device at the ejector or pusher mechanism, the carriage being shown holding a package opposite said mechanism.

Fig. 9 is a sectional plan showing the package being slit by the knife.

Fig. 10 is an elevation of a modified form of the device looking toward the wall adjacent the knife, an additional knife being provided outside of the casing for cutting off the flap, and

Fig. 11 is a partial section taken along the line 11—11 of Fig. 10.

The device has side walls 12 and 13 and an arculate front wall, one part 14 of which is attached to sidewall 12 and the other part 15 of which is attached to sidewall 13. A space is left between parts 14 and 15 giving rise to slot 16. The curvature of parts 14 and 15 is circular. Shaft 17 is journaled at its ends in side walls 12 and 13. Fixedly mounted on shaft 17 is segmental gear 18. A crooked arm 19 is fixed to gear 18, said arm

extending up through slot 16 and having handle 20 mounted on its outer end. Attached to arm 19, just inside front wall parts 14 and 15, is a channel-shaped package carrier 21 for holding the cigarette package 22 with its ends facing

side walls 12 and 13, Figs. 6, 8 and 9. With arm 19 and carrier 21 in its extreme upper position, the carrier comes opposite tapered bulges 23 in side walls 12 and 13. This permits the easy introduction of a package 22 into carrier 21 through opening 31 provided in the slotted front wall

55

formed of parts 14 and 15, Fig. 1. When carrier 21 with the package in it is swung down, the package is squeezed in by the tapered sides of bulges 23 so that when it passes down from the bulges it is held compressed between side walls 12 and 13. As will be seen later on, this is important for the slitting of the package without injuring the cigarettes in it.

Another shaft, shaft 24, is journaled in side walls 12 and 13. Pinion 25, which meshes with segmental gear 18, is fixed to shaft 24. Ratchet wheel 26, Fig. 4, which is inside hollow hub or casing 27 of circular knife 28, is also fixed to shaft 24. Knife 28 is loose on shaft 24. Pawl 29 and its spring 30 are fixed to knife 28. When carrier 21 is moved down by arm 19, segmental gear 18 rotates pinion 25 in a clockwise direction as viewed in Fig. 6, causing ratchet wheel 26 also to move in this direction. Wheel 26 engages pawl 29 causing knife 28 to rotate in a clockwise direction. When carrier 21 is moved to its lowest position, segmental gear 18 ceases to rotate pinion 25 and ratchet wheel 26, but because of its inertia, knife 28 will continue to turn for a while, pawl 29 slipping over the teeth of wheel 26. Because of this lost motion, different portions of the cutting edge of the knife are presented toward subsequent packages 22 as the latter are moved against the knife by the swinging down of arm 19. The swinging down of arm 19 moves carrier 21 to push a part of package 22 near one end against the knife, partially slitting the wrapper as seen in Fig. 2. The spacing of side walls 12 and 13 is such, especially just above and opposite knife 28, as to squeeze the ends of the package between them so that the knife, which is in close proximity to side wall 13 will just slice the wrapper without injuring the ends of the cigarettes. A recess 61 is provided in wall 13 for the accommodation of knife 28. It is to be observed that the width of carrier 21 is less than the length of package 22 so that both ends of the package project beyond the carrier, permitting operations to be performed on said ends. So far the mechanism for slitting the package has been described. The mechanism for pushing out a few cigarettes from the slit package, as shown in Fig. 3, will now be described.

Extending over opening 32 in side wall 12 and spot welded to said wall, Figs. 1, 5 and 8 is a channel-shaped support 33 in the outstanding legs of which is mounted stub shaft 34. Loosely mounted on shaft 34 is a pusher plate denoted in its entirety by the numeral 35. An opening 36 is provided in plate 35, through which one end of spring 37 projects, the spring being coiled about shaft 34 with its other end, not seen, engaging support 33. Spring 37 acts to resist yieldingly the rotation of plate 35, Fig. 8 in a clockwise direction. The device in Fig. 8 is viewed in the same general direction as indicated by line 5-5 in Fig. 6, except that arm 19 has been broken off and the carrier 21 has been swung down past knife 28. Further motion of carrier 21, as viewed in Fig. 8, would be down. As seen in said figure, the main portion of package 22 is beyond plate 35, only shoulder 38 of said plate being at the corner of the package at the opposite end thereof from where it was slit by knife 28 to form flap 39. In swinging down, carrier 21, lug 40, on said carrier, presses down on tongue 41, effecting clockwise rotation of plate 35 causing shoulder 38 to push against the end of the package forcing out a few cigarettes 42 against flap 39. When carrier 21 has

swung down to its lowermost position, package 22 is discharged by gravity through opening 43 in the casing and tongue 41 rides on end wall 44 of lug 40. The discharged package is caught on platform 45 and held thereon by stops 46.

A tension spring 47, Figs. 5 and 6 is fastened at its bottom to stay 48 and at its top to lug 49 on arm 19. Said spring is placed under initial tension. The swinging down of arm 19 about its pivotal axis, extends spring 47, so that when said arm is released it will be pulled up by the spring until it strikes stay 50. A forked plate spring 51, attached to arm 19, is arranged to pinch stay 50 for releasably fastening said arm in its upper position to prevent its rebounding.

In the form of the device previously described the spacing of side walls is such that the ends of package 22 are squeezed between said side walls 12 and 13 at their portions opposite knife 28, so as to insure the proper gauging of the package between side wall 13 adjacent the knife and the knife for the proper cutting of the wrapper of the package. In Fig. 7, a modified form of means is provided to ensure the proper gauging of the package. In this modified form, the spacing of the side walls 12 and 13 is not wholly relied upon properly to gauge the package at the knife, but a plate spring 52 is fastened to wall 12 in the path of package 22 as it is swung down by arm 19, so that said spring is flattened by an end of the package as the opposite end of the package is pressed against side wall 13 and is entered into and slit by knife 28.

As described thus far, the package opener is capable only of partially cutting the package near one end to produce a flap. The modification of the opener in Figs. 10 and 11 is capable of cutting off the flap. In this form knife shaft 53 extends sufficiently through side wall 13 to have helical gear 54 fixed to its outer end. Short shaft 55 is rotatably mounted in support 56, the latter being welded to side wall 13. Fixed to one end of shaft 55 and meshing with helical gear 54 is a mating helical gear 56. The other end of shaft 55 has cut-off knife 57 fixedly mounted on it. Knife 57 projects through side wall 13 in slot 58 so that it can slice off flap 39 as it is moved past by carrier 21. It is to be noted that the swinging down of arm 19 rotates knife 57.

I claim:

1. A cigarette package opener comprising a carrier for holding the package, a pivotally mounted arm supporting said carrier, a rotatably concentrically mounted circular knife, the pivotal axis of the arm being spaced from and parallel to the axis of rotation of the knife, mechanism, connecting the arm and the knife, driven by the swinging down of the arm about its pivotal axis to rotate the knife, said swinging of the arm moving the carrier to cause a part of the package near one end to be moved against the knife, partially slitting its wrapper thereby, clear of the adjacent end of the cigarettes.

2. A cigarette package opener comprising a casing, a carrier for holding the package, an arm pivotally mounted on the casing supporting said carrier, said arm in its upper position holding the carrier opposite an opening provided in the casing for the reception of the package, a knife rotatably mounted on the casing, mechanism, connecting the arm and the knife, driven by the swinging down of the arm about its pivotal axis to rotate the knife, said swinging down of the

arm moving the carrier to cause a part of the package near one end to be moved against the knife partially slitting its wrapper thereby clear of the adjacent end of the cigarettes, said carrier being sufficiently tilted to discharge the package by gravity when the arm is swung down to substantially the lowermost position.

3. A cigarette package opener comprising a casing having a pair of side walls, a carrier for moving the package between the side walls, a pivotally mounted arm, having its pivotal axis extending substantially perpendicular to the side walls, supporting said carrier, a rotatably mounted knife with its axis of rotation substantially perpendicular to the side walls, mechanism, connecting the arm and the knife, actuated by the swinging down of the arm about its pivotal axis to drive the knife to rotate about its axis of rotation, said knife being located substantially the thickness of the wrapper of the package from one of said side walls, said swinging of the arm moving the carrier to push a part of the package against the cutting edge of the knife causing to be slit a part of the wrapper along one side of the package.

4. A cigarette package opener comprising a casing having a pair of side walls, a carrier for moving the package between the side walls, a pivotally mounted arm supporting the carrier and having its pivotal axis extending substantially perpendicular to the side walls, a knife rotatably mounted in close proximity to one of the side walls, the axis of rotation of the knife being substantially perpendicular to the sidewall adjacent to it, mechanism, connecting the arm and the knife, actuated by the swinging down of the arm about its pivotal axis to effect the rotation of the knife, and means for forcing one end of the package against the side wall adjacent the knife, said swinging of the arm moving the carrier to push a part of one end of the package against the rotating cutting edge of the knife.

5. A cigarette package opener comprising a casing having a pair of side walls, a carrier for moving the package between the side walls with the ends of the package facing said walls, a pivotally mounted arm supporting the carrier and having its pivotal axis extending substantially perpendicular to the side walls, a knife rotatably mounted in close proximity to one of the side walls, the axis of rotation of the knife being substantially perpendicular to the side wall adjacent to it, and mechanism, connecting the arm and the knife, actuated by the swinging down of the arm about its pivotal axis to drive the knife to rotate about its axis of rotation, the spacing of the sidewalls at the knife being such as to squeeze the ends of the package between them, said swinging of the arm moving the carrier to push a part of one end of the package against the rotating cutting edge of the knife.

6. A cigarette package opener comprising a casing having a pair of side walls, a carrier for moving the package between the side walls with opposite ends of the package facing said walls, an arm supporting the carrier and mounted to move the package between the side walls, a knife mounted substantially parallel to and in close proximity to the first of the side walls, and spring actuated means mounted substantially opposite the knife on the second of said side walls for forcing one of said ends against said first side wall adjacent the knife as the motion of the arm

moves the carrier to push a part of said latter end of the package against the cutting edge of the knife.

7. A cigarette package opener comprising a casing having a pair of side walls, a carrier for moving the package between the side walls, a pivotally mounted arm having its pivotal axis extending substantially perpendicular to the side walls, the outer end of the arm extending outside of the casing, the carrier being supported by the arm inside of the casing, said arm in its upper position holding the carrier opposite an opening provided in the casing for the reception of the package, the side walls being bulged outward at said opening, a knife rotatably mounted in close proximity to a portion of one of the side walls, the axis of rotation of the knife being substantially perpendicular to said portion, mechanism, connecting the arm and the knife, actuated by the swinging down of the arm about its pivotal axis to effect the rotation of the knife, said swinging down of the arm moving the carrier to push a part of one end of the package against the rotating cutting edge of the knife, said latter end being held against the sidewall at the portion adjacent the knife.

8. A cigarette package opener comprising a casing having a pair of side walls and an arcuate front wall having a longitudinal slot therein, a pivotally mounted arm having its pivotal axis extending substantially perpendicular to the side walls and substantially coincident with the center of curvature of the front wall, the outer end of the arm extending through said slot to the outside of said front wall, a rotatably mounted knife, mechanism connecting the arm and the knife, actuated by the swinging down of the arm to effect the rotation of the knife, and a carrier supported by said arm moving the package substantially concentrically with and just inside the front wall when the arm is swung down about its pivotal axis causing a part of the package near one end to be moved against the knife, partially slitting its wrapper thereby.

9. A cigarette package opener comprising a casing, a carrier for holding the package, a pivotally mounted arm supporting the carrier, said arm in its upper position holding the carrier opposite an opening provided in the casing for the reception of the package, a rotatably mounted knife inside the casing, mechanism connecting the arm and the knife, actuated by the swinging down of the arm about its pivotal axis to effect the rotation of the knife, said swinging down of the arm moving the carrier to cause a part of the package near one end to be moved against the knife partially slitting its wrapper thereby, said carrier being sufficiently tilted to discharge the package by gravity when the arm is swung down to substantially its lowermost position, an opening being provided in the casing for the passage therethrough of the package discharged from the carrier, and a platform on the casing below said latter opening for receiving the discharged package.

10. A cigarette package opener comprising a casing having a pair of substantially parallel side walls, a carrier for moving the package between the side walls, a pivotally mounted arm supporting the carrier and having its pivotal axis extending substantially perpendicular to the side walls, a rotatably mounted knife with its axis of rotation substantially perpendicular to the side

walls, mechanism, operatively connecting the arm and the knife, actuated by the swinging down of the arm about its pivotal axis to effect the rotation of the knife and a spring yieldingly resisting the manual force required for swinging down the arm, returning the latter when released to its upper position, said swinging down of the arm moving the carrier to cause a part of the package near one end to be moved against the knife partially slitting its wrapper thereby.

11. A cigarette package opener comprising a casing having a pair of side walls, a carrier for moving the package between the side walls, a pivotally mounted arm supporting the carrier and having its pivotal axis extending substantially perpendicular to the side walls, a rotatably mounted knife with its axis of rotation substantially perpendicular to the side walls, mechanism, operatively connecting the arm and the knife, actuated by the swinging down of the arm about its pivotal axis to effect the rotation of the knife, said swinging down of the arm moving the carrier to cause a part of the package near one end to be moved against the knife partially slitting its wrapper thereby, and a spring catch having mating parts, one part thereof being carried by the arm and the other part being attached to the casing for releasably holding the arm in its upper portion.

12. A cigarette package opener comprising a carrier for holding the package, a pivotally mounted arm supporting said carrier, a rotatably mounted knife, gear means rotatable in fixed relation to the arm and a gear coaxially mounted with the knife and engaging said gear means, the swinging down of the arm rotating said gear means, effecting the rotation of said gear and the knife, the axes of rotation of the arm and the knife being substantially parallel said swinging down of the arm moving the carrier to cause a part of the package near one end to be moved against the knife while rotating, partially slitting its wrapper thereby.

13. A cigarette package opener comprising a carrier for holding the package, a movably mounted arm supporting the carrier, a rotatably concentrically mounted circular knife, the axis of rotation of the knife being substantially perpendicular to the direction of motion of the arm, mechanism operatively connecting the arm and the knife releasably engaging the knife for effecting the rotation of the latter in one direction only, said mechanism being driven by the motion of the arm to rotate the knife, the relative locations of the arm, carrier and knife being such that said motion of the arm enables moving the carrier to cause a part of the package near one end to be moved against the knife and beyond it during the rotation of the latter, partially slitting the package thereby and permitting the knife to rotate by its own inertia when the arm is stopped with the package beyond the knife.

14. A cigarette package opener comprising a casing, a carrier for holding the package, a pivotally mounted arm supporting the carrier, a shaft extending transversely of the casing, a knife mounted on the shaft, the pivotal axis of the arm being substantially parallel to said shaft, a gear mounted on the shaft, ratchet mechanism fixed to the gear and releasably engaging the knife for driving the latter in one direction only, gear means, rotatable in fixed relation to the arm, engaging said gear, the swinging down of the arm

rotating the gear and causing the ratchet mechanism to rotate the knife, the relative location of the knife, carrier and pivotal axis of the arm being such that said swinging down of the arm enables moving the carrier to cause part of the package near one end to be moved against the knife and beyond it during the rotation of the latter, partially slitting the package thereby and permitting the knife to rotate by its own inertia when the arm is stopped with the package beyond the knife.

15. A cigarette package opener comprising a carrier for holding the package, a pivotally mounted arm supporting said carrier, a rotatably mounted knife, mechanism, operatively connecting the arm and the knife, actuated by the swinging down of the arm about its pivotal axis to effect the rotation of the knife, said swinging down of the arm moving the carrier to cause a part of the package near one end to be moved against the knife, partially slitting its wrapper thereby to form a flap, and a second knife rotatably mounted at an angle with the first knife, said mechanism also operatively connecting the arm and the second knife, said swinging down of the arm effecting also the rotation of the second knife and moving the package against the second knife, cutting off the flap formed by the first knife.

16. A cigarette package opener comprising a casing, a carrier for holding the package, a pivotally mounted arm supporting the carrier, a shaft extending transversely through the casing, a knife loosely mounted on the shaft, a gear fixedly mounted on the shaft, ratchet mechanism fixed to the gear and releasably engaging the knife for driving the latter in one direction only, a second gear fixed to the arm meshing with said first gear, a third gear fixed to said shaft outside of the casing, a stub shaft rotatably mounted on the outside of the casing at an angle with the first shaft, a fourth gear fixed to the stub shaft and meshing with the third gear, a second knife fixedly mounted on the stub shaft, the swinging down of the arm rotating the gears and the second knife and causing the ratchet mechanism to rotate the first knife, said swinging down of the arm moving the carrier first to cause part of the package near one end to be moved against the first knife during the rotation of the latter, partially slitting the package thereby to form a flap and then moving the package against the second knife during the rotation of the latter, cutting off the flap.

17. A cigarette package opener comprising movably mounted means for carrying the package along a predetermined path substantially parallel to a plane, a knife for slitting the package partly across one end to form a flap as the package is moved along its path past the knife, and a pivotally mounted pusher with its pivotal axis substantially parallel to said plane, a part of said means engaging the pusher upon motion of the package beyond the knife, swinging the pusher thereby across the path of the package to push against the opposite end of the package from the slit end, causing one or more cigarettes to project from the package at the slit end.

18. A cigarette package opener comprising a casing having a pair of side walls, movably mounted means for moving the package between the side walls, a knife mounted in close proximity to one of the side walls, slitting the package partly across one end to form a flap as the package is

moved past the knife, and a pivotally mounted pusher adjacent the other side wall, the pivotal axis of the pusher being substantially parallel to said other side wall, a part of said means engaging the pusher when the package is moved past the knife, swinging the pusher toward the first of said side walls against the opposite end of the package from the first of said sidewalls, causing one or more cigarettes to be pushed partly out of the package.

19. A cigarette package opener having a pair of side walls, a carrier for moving the package between the side walls with the opposite ends of the package facing said walls, a movable knife mounted in close proximity to one of the said side walls and substantially parallel thereto, and means projecting into the space between the walls for forcing one of said ends of the package against said side wall close to the knife as the package is moved between said walls past said means, said motion of the carrier pushing said latter end against the cutting edge of the knife.

20. A cigarette package opener comprising a casing having a pair of oppositely disposed side walls, a carrier for moving the package between the side walls with the opposite ends of the package facing said walls, an arm supporting the carrier mounted to move the package between the side walls, a knife rotatably mounted in close proximity to one of the side walls, the axis of rotation of the knife being substantially perpendicular to the side wall adjacent to it, and mechanism connecting the arm and the knife actuated by the motion of the arm to rotate the knife, the spacing of the side walls at the knife being such as to squeeze said ends of the package between them with one end against the wall close to the knife, said motion of the arm moving the carrier to push a part of one of said ends against the rotating cutting edge of the knife.

21. A cigarette package opener having a pair of side walls, a carrier for moving the package between the side walls with opposite ends of the package facing said walls, and a knife mounted in close proximity to the first of the side walls and substantially parallel thereto, the spacing of the side walls at the knife being such as to squeeze said ends of the package between them with one end against the wall close to the knife, said motion of the carrier pushing one of said ends of the package against the cutting edge of the knife.

22. A cigarette package opener having a pair of oppositely disposed side walls, a carrier for moving the package between the side walls with opposite ends of the package facing said walls, a knife mounted in close proximity to one of said walls and substantially parallel thereto for slitting the package at one of said ends as it moves past, said walls being spaced sufficiently for the introduction of the package at its initial posi-

tion, the distance between the side walls being less near the knife than at said initial position to compress the package as it is moved and to force the end to be slit against the wall close to the knife.

5 23. A cigarette package opening device comprising means for moving the package through the device, means for slitting the package partly across near one end at one location on the path 10 traversed by the package through the device, and a member mounted on the device to project into said path, said member being located on the device to be passed by the package as it is moved through the device after the package has been slit, the projection of said member causing it to push against the package at the package's opposite end from where slit for causing one or more cigarettes to project from the package at the slit as the package is moved by said member.

20 24. A cigarette package opening device comprising means for effecting the slitting of the package partly across near one end to form a flap, and a member movably mounted and located on the device to be actuated by said means after the package has been slit to push against the package at the package's opposite end from where slit for causing one or more cigarettes to project from the package at the slit.

30 25. A cigarette package opening device comprising means for moving the package through the device, means for slitting the package partly across near one end as the package is moved through the device, and a member rotatably mounted and located on the device to be actuated by the means for moving the package as the package passes by it to rotate into the path of the package and push against the package at the package's opposite end from where slit after the package has been slit for causing one or more cigarettes to project from the package at the slit.

35 40 26. A cigarette package opening device comprising means for effecting the removal of a corner of the device, and a member movably mounted and located on the device to be actuated by said means after the corner has been removed to push against the package at the package's opposite end from where said corner has been removed for causing one or more cigarettes to project from the package where said corner was removed.
